PIPE FOR SMOKING TOBACCO

Frank J. Garrison, 1031 Riverview Ave., Dayton, Ohio
Filed Oct. 16, 1961, Ser. No. 145,201
2 Claims. (Cl. 131—203)

This invention relates to an improved pipe for smoking tobacco.

It is among the objects of the present invention to provide a pipe for smoking tobacco with means for accumulating and trapping the foul tasting moisture usually found in a pipe after repeated use. This means substantially prevents the moisture from being drawn through the bit into the mouth of the user.

A further object of the present invention is to provide a pipe with moisture accumulating and trapping means, which is remote from the bit of the pipe and over or through which the smoke does not pass as it is drawn from the bowl of the pipe, through the bit and into the mouth of the user.

Further objects and advantages of the present invention will be apparent from the following description, reference being had to the accompanying drawings showing preferred forms of construction embodying the features of the present invention.

In the drawings:

FIG. 1 illustrates a pipe having a one-piece stem and bit to which the bowl portion of the pipe is removably attached, this bowl portion cooperating with the stem to form a moisture accumulating and trapping chamber.

FIG. 2 shows a pipe similar to the one shown in FIG. 1, the stem, however, being removably attached to the bit and forming an intermediate chamber in said stem.

FIG. 3 shows a pipe having a one-piece stem and bowl, the bit being removably attached to the stem and forms an intermediate chamber in the stem. This chamber is remote from but directly connected with the moisture accumulating and trapping chamber in the stem and independent of the bowl portion thereof.

FIG. 4 is a detail, elevational view of the removable bowl portion of the pipe.

In smoking tobacco in a pipe, a very undesirable condition presents itself, that is, the accumulation of a foul tasting moisture in the smoke conducting passages of the pipe, caused by condensation and the added drivel by the user of the pipe.

Attempts have been made to mitigate this condition by providing moisture accumulators or absorbers directly inside the smoke conducting passage of the pipe. Such arrangements are effective for a very short period of use for, as the deterring elements in the smoke passage become charged with the ill tasting moisture, the smoke laden air being drawn through and over the said moisture charged elements will become contaminated and take up the foul taste of the moisture. Eventually the moisture itself may be drawn into the mouth of the smoker with the ill tasting, smoke laden air.

This inefficient arrangement and its undesirable effects are practically avoided in the pipe of the present invention. Here the moisture accumulating chamber and its contained absorbing element is remote from the pipe passage through which the smoke laden air is drawn and conducted to the mouth of the user. Said chamber and its contained element is connected with the smoke conducting pipe passage at a point remote from said chamber, thereby eliminating direct contact of the smoke laden air with the accumulated, foul tasting moisture in the said chamber and its contained element. This feature permits the moisture, particularly the smoker's drivel to flow directly into the accumulating chamber, remote from the smoke passage of the pipe. Suction on the pipe stem for smoking purposes will have no substantial with-

2

drawing effect upon the moisture in the accumulating chamber.

Referring to the drawings, particularly FIG. 1, the pipe has a main body portion 20, and integral therewith the stem portion 22, and bit portion 23. These three portions may be made of any suitable material capable of being molded, such as plastics or the like. A bowl 21, preferably made of wood, and hollowed out to form the tobacco combustion chamber 26, has an exteriorly threaded extension 27, which is received by the interiorly threaded recess in the body 20 of the pipe, for removably attaching the bowl to 21 to said pipe body. The inner surface of bowl extension 27 forms the ceiling of the moisture accumulating chamber 24 in said recess. An annular groove 28 is provided in its extension 27, said groove being in communication with the interior 26 of the bowl 21 through passage 29. A passage 25 opens into the moisture receiving chamber 24 and extends throughout the entire length of the integral stem and bit portions 22 and 23 respectively. A smoke conducting conduit 26 has its one end opening into the passage 25 at a point remote from the moisture chamber 24, and extends upwardly through the body portion 20 of the pipe and communicates with the interior of the bowl through groove 28 and passage 29.

To assist in the retention of the fluid moisture accumulated in the chamber 24, a wad or pad of absorbent material 30 is replaceable held therein by the bowl 21. This substantially prevents the back flow of liquid moisture from chamber 24 into the bit 23.

When this pipe is used, air drawn through the burning tobacco in bowl 21 will become smoke laden and pass through opening passage 29 into the communicating, downwardly inclined passage 26, connecting passage or duct 25, and enter into the user's mouth. Inasmuch as this flow of smoke laden air is remote from, and in no way passes over or through the foul tasting moisture accumulated in chamber 24, the smoke laden air, drawn into the mouth of the user, will not be contaminated. Inclination 40 of the smoke passage 26, upwardly from its point of connection with the duct 25, will substantially prevent the drivel of the smoker to flow into the bowl area of the pipe, but on the contrary, said drivel will flow through duct 25 into the moisture accumulating chamber 24.

The pipe shown in FIG. 2, is substantially like the one shown in FIG. 1, excepting that the bit portion 123 is removably attached to the stem portion 122. Here the end of the stem portion 122 has a recess 131, which receives the reduced end 132 of the bit portion 123. The recess 50 131 in the stem is longer than the reduced portion 132 of the bit 123, thus forming the intermediate chamber 133 within the stem 122. Duct 134 in the stem directly connects the intermediate chamber with the moisture accumulating chamber 124. Duct 125 in the bit 123 opens into 55 the intermediate chamber 133. The inclined smoke conduit 126 opens into the intermediate chamber 133 and communicates with the interior of the bowl 121 through passage 129 in said bowl. An absorbing pad 130 is provided in the chamber 124. It will be noted that the intermediate chamber is remote from the accumulating chamber and that the smoke conduit opens into the upper area of said intermediate chamber 133.

The pipe shown in FIG. 3, differs from those of FIGS. 1 and 2 in that the bowl portion 221 is not removable, but is integral with the stem portion 222. Like the pipe of FIG. 2, it has a detachable bit portion 223, provided with a reduced diameter end 232 which is insertable into recess 231 in the end of the stem portion 222, and forms an intermediate chamber 233 therein. In the bottom of 65 the stem portion, contiguous to but not in direct communication with the bowl portion 221, there is provided an interiorly threaded recess having a removable sealing plug

240 which forms the moisture accumulating chamber 224 within said recess. A moisture absorbing wad or pad 230 in said chamber is replaceable by removal of said plug 240. A smoke conduit 226 provides a downwardly inclined communication between the interior of the bowl portion 221 and the intermediate chamber at its upper area. Duct 234 in the stem portion 222 directly connects the intermediate chamber 233 with the moisture accumulating chamber 224. The duct 225 in stem portion 223 opens directly into the intermediate chamber 233.

The features of the present invention are readily adaptable to be embodied in a pipe having a curved stem and bit. These features substantially isolate the flow of the smoke laden air from the area of moisture accumulation and consequently said air will not be contaminated and ruined by the foul tasting, accumulated moisture.

In the proposed constructions the pipe may easily be cleaned and the absorbent wad or pad may readily be removed and replaced with a wad of cotton, sponge or other material having moisture absorbing qualities.

What is claimed is as follows:

1. A pipe for smoking tobacco, said pipe consisting of a stem having a bit portion, there being a recess in the stem adjacent its end opposite the bit portion, a bowl removably secured in said recess and having a bottom wall forming a top closure member for said recess, this recess providing a moisture receiving chamber, a pair of diverging ducts extending lengthwise of the stem and having a lower conduit providing an unrestricted passage constituting the sole communication between the end of the bit portion and the moisture receiving chamber, and having an upper downwardly inclined conduit connecting the in-

terior of the bowl with the duct at a point substantially at the midpoint of said pipe so as to be remote from the said chamber, and a moisture absorbing pad in said chamber.

5 2. A pipe for smoking tobacco, said pipe consisting of a stem having a bit portion, there being a recess in the stem adjacent its end opposite the bit portion, a bowl removably secured in said recess and having a bottom wall forming a top closure member for said recess, this recess providing a moisture receiving chamber, a pair of diverging ducts extending lengthwise of the stem and having a lower conduit providing an unrestricted passage constituting the sole communication between the end of the bit portion and the moisture receiving chamber, and having an upper downwardly inclined conduit connecting the interior of the bowl with the duct at a point substantially at the midpoint of said pipe so as to be remote from the said chamber, and a moisture absorbing pad in said chamber, the walls of said recess having threads formed thereon, the lower end of said bowl having threads formed thereon for engagement with said first named threads.
